ENGINE CONTROL APPARATUS

John B. Dyer, Dayton, Ohio, assignor to General Motors Corporation, Detroit, Mich., a corporation of Delaware

Refiled for abandoned application Serial No. 685,662, August 18, 1933. This application March 6, 1937, Serial No. 129,346

13 Claims.

(Cl. 290—38)

This invention relates to apparatus for controlling the operation of internal combustion engines, more particularly those of automotive vehicles and specifically to apparatus for controlling the starting devices of such engines.

Heretofore electrically operated means for causing the starting motor to become operative to start the engine has been provided which is so constructed that it employs a minimum of current during operation so as to exhaust the battery to the least possible extent during the starting operation and to reduce the cost of such electrical devices to as great an extent as possible.

Semi-automatic means to control the electrically operated starter control means has been provided which is so constructed that the electrically operated means is caused to operate in response to operation of one or more of the control devices which must be actuated by the operator of the engine or vehicle in controlling the operation thereof under ordinary operating conditions, but is adapted to automatically render the starting motor inoperative in response to operation of the engine itself, and to prevent the starting motor from becoming operative as long as the engine continues to run under its own power.

It is one object of this invention to provide a semi-automatic control means for the electrically operated starter control devices which can by a simple adjustment be changed from a semi-automatic device such as described, to a full automatic control which is effective to cause the starting motor to operate upon closing of the ignition switch without actuation of other control devices, but which is operable by the engine to cause the starting motor to cease operating when the engine begins to run under its own power.

Another object of the invention is to provide a control switch for the electrically operated starter control device, which may be closed by operation of the accelerator pedal which controls the quantity of combustible mixture supplied to the engine or otherwise and which is opened by action of engine suction, but is so constructed that the switch is opened under the lowest possible suction that is maintained under any possible operating conditions; and to provide means to hold the switch in closed position until the switch operating means is permitted to return to its normal inoperative position, whereby the control switch is held open during any possible operation of the engine under its own power, but is prevented from opening during the cranking of the engine.

55 Further objects and advantages of the present

invention will be apparent from the following description, reference being had to the accompanying drawings wherein a preferred embodiment of the present invention is clearly shown.

This application is a substantial duplicate of 5 application No. 685,662, filed August 18, 1933 which has become abandoned.

In the drawings:

Fig. 1 is a wiring diagram of a starter control system constructed according to the present invention and controlling a magnetic switch for controlling the circuit of a starting motor which is adapted to shift the starter drive pinion into and out of engagement with the flywheel gear automatically.

10 Fig. 2 is a similar control system controlling an electromagnet which controls the circuit of a starting motor having a drive pinion which is moved into and out of engagement with the flywheel gear by means of said electromagnet.

15 Fig. 3 is a wiring diagram similar to Fig. 2 but showing a manually operable push button switch for controlling the electromagnet.

20 Fig. 4 is an end elevation of the switch A shown in Fig. 1.

25 Fig. 5 is a view on the line 5—5 of Fig. 4.

Fig. 6 is a perspective view of two details of construction of the switch A.

30 Fig. 7 is a similar perspective view of the same details showing a modified form of the switch A.

35 Referring to Fig. 1 of the drawings, the starting motor is indicated at 20 and has a ground connection 22. The starting motor is adapted to operate a starter drive in which the pinion 35 driven by the starting motor is automatically moved into engagement with the engine flywheel gear when the starting motor switch is closed and is automatically disengaged therefrom when the engine begins to operate under its own power. 40 The well known Bendix drive is a starter drive of this character and has not been illustrated in detail herein as it is thought that such illustration is unnecessary.

45 The circuit of the starting motor is closed by an electromagnet 24 having an armature 26 which is adapted to be moved to the left in Fig. 1 when the magnet is energized to close the starting motor switch in a manner more specifically described hereinafter.

50 The circuit of the starting motor comprises the ground connection previously referred to and a wire 28 which is connected to one fixed contact 30 of the starting motor switch which has another fixed contact 32 connected by wire 34 with 55

a wire 36 which leads from the battery 38 to a generator 40 which is grounded at 42, the usual cut-out relay 44 being provided between the generator and the battery. The battery is grounded 5 by the connection 46. A movable contact 48 is carried by the armature 26 of the magnet 24, and is adapted to be moved into engagement with the two fixed contacts 30 and 32 when the magnet 24 is energized as will be later described. 10 When the contact 48 is engaged with the two fixed contacts, current will flow from the battery to ground through the connection 46 and from the battery through the wires 36 and 34, the starting motor switch and wire 28 to the starting 15 motor and through the connection 22 to ground again. Thus whenever the magnet 24 is energized, the starting motor is rendered operative to crank the engine and the starting motor will remain operative as long as the starting motor 20 switch above referred to, is closed, although the driving pinion operated by the starting motor will be disengaged from the flywheel gear as soon as the engine is operating under its own power, as is always the case when a Bendix drive is employed. The magnet must, however, be de-energized so as to cause the starting motor switch to open as soon as the engine is running under its own power, or the pinion would be moved back 25 into engagement with the flywheel gear and damage would result, and means are provided to effect this function and to prevent the starting motor from becoming operative during operation of the engine, as set forth later.

The magnet 24 is provided with two coils 50 and 52 having different numbers of turns for a purpose set forth hereinafter and the energization of the magnet is effected by the closing of the ignition switch and a second switch indicated in its entirety by the letter A, which is adapted to 35 be closed by movement of the accelerator pedal to open the carburetor throttle and is adapted to be opened by the action of engine suction when the engine is operating under its own power. The circuit connections for the magnet 40 which will now be described, comprise a wire 54 leading to the movable contact 56 of the ignition switch which has a stationary contact 58 connected by a wire 60 to the ignition system of the engine. A wire 62 leads from the wire 60 to a 45 fixed contact 64 of the switch A which is provided with another fixed contact 66 and a movable contact 68 which is adapted to be moved to engage the two fixed contacts by an operating arm 70 which is adapted to be connected by any 50 suitable form of operating connection to the accelerator pedal. The fixed contact 66 is connected by a wire 72 which leads to both of the coils 50 and 52, the coil 50 being grounded by the connection 74 while the coil 52 is connected 55 by a wire 76 with the wire 28 which leads from the fixed contact 30 of the starting motor switch to the starting motor. Obviously, when the ignition switch and the switch A are closed, current will flow from the battery to ground through the 60 wire 46 and from the battery through the wires 36 and 54, the ignition switch, wires 60 and 62, the switch A and wire 72 to both coils of the magnet and will flow through both coils of the magnet directly through the coil 50 and the 65 ground connection 74 to ground and through the coil 52, wires 76 and 28, the starting motor and the ground connection 22 of said motor to ground. Thus both coils of the magnet are energized and the armature 26 is moved to the left 70 by a force which is due to the effect of both coils. 75

As soon as the contact 48 engages the contacts 30 and 32, the coil 52 is shunted out and becomes ineffective to exert any pull on the armature because as will be obvious, on inspection of Fig. 1, after the contact 48 engages contacts 30 and 32, 5 current will flow from the wire 36 directly through the wire 34 and through the starting motor switch, wire 28 and the starting motor to ground, and of course will simultaneously flow through the path above described to the coil 50 and 10 through the connections 74 to ground, but there will be no appreciable flow of current from the wire 12 through the coil 52 and wire 76 because this coil and such wire will be shunted out owing to the direct flow of current through the wire 36 15 and the starting motor switch to the wire 28 and to ground. Therefore, after the starting motor switch is closed and during the operation of the starting motor to crank the engine, the armature 26 is held in its left hand or switch closing 20 position only by the force exerted through the energization of the coil 50 which, while sufficient to hold the armature in such position, is insufficient to move it from its initial position. This is due to the fact that after the armature 25 has been shifted, the inertia of the parts and the effect of the air gap do not have to be overcome so that less force is required to hold the armature in switch closed position than to move it to switch closing position. 30

Upon opening of the ignition switch manually, or upon opening of the switch A by engine suction as previously referred to, the holding coil 50 is necessarily de-energized so that the armature of the magnet will be restored to its original position, a spring 78 being provided for that purpose. The specific construction of the magnet and the arrangement of the switch contact 48 relative to the armature forms no part of this invention and the structural details of the magnet are not illustrated herein. For the purpose of this disclosure it is sufficient to say that the contact 48 is moved against the pressure of a spring 80 which lies between the contact and a fixed element 82 to close the switch and after the switch 45 is closed a spring 84 on the opposite side of the contact is compressed by movement of the armature so that the switch is held closed with a heavy pressure.

The construction of the magnet 24 may be varied within certain limits, but it is desirable that the coil 50 shall contain a smaller number of turns than the coil 52 and the resistance of the coil 50 should be higher than the coil 52 so that the flow of current through the coil 50 is as low 50 as possible to insure that the armature be held in switch closed position during the cranking operation, in order to discharge the battery as little as possible during the cranking operation. The flow of current through the coil 52 is very 55 brief as it takes an almost imperceptible time to effect closing of the starting motor switch so that during most of the starting operation while the starting motor switch is closed and the starting motor is in operation to crank the engine, there 60 is only a relatively small current flowing through the coil 50. As has been stated previously, it is necessary to have the number of turns in the coil 52 greater than those in the outer coil. This is true because when either the ignition switch 65 or the switch A is opened to cause the starting motor to become inoperative, the starter switch being still closed, current will flow from the battery through the starter switch and thence through the coils of the magnet to the ground, 70 75

the direction of current in the inner coil being the reverse of that in the outer coil.

As a concrete example of this operation it may be assumed that the switch A is opened by suction and the starter switch should open immediately so as to cause the starting motor to become inoperative and prevent the automatic movement of the driving pinion back into engagement with the flywheel gear after it has been disengaged therefrom. On opening of the switch A however, current will flow from the battery to ground through the connection 46 and from the battery through wires 36, 34, the starter switch, wires 28 and 76 to the coil 52, thence through the other coil 50 and a connection 74 to the ground, the direction of flow through the coil 52 being reversed, while the direction of flow through the coil 50 remains the same as before the opening of the switch A. Under these conditions the two coils tend to neutralize each other and in order to insure that the magnetic flux passes through the zero point immediately so that the magnet will be completely de-energized and a slightly larger number of turns are used in the inner coil. With this arrangement as the flux passes through the zero point upon the reversal of polarity of the inner coil on the opening of the switch A or the ignition switch, the starter switch is also immediately opened by the spring 80 and the spring 78 retracts the armature to its original position.

Theoretically, it might be possible to effect opening of the switch with coils having the same number of turns, but owing to residual magnetism of the magnet, inaccuracies in the wire resulting in varied resistance, and manufacturing inaccuracies, it is impossible to use coils of the same number of turns as the magnetic flux might not reach zero under all circumstances. To make sure that the flux pressure does always pass through the zero point, it is necessary to have at least a few more turns in the inner coil than in the outer.

As stated previously, the switch A is adapted to be closed by operation of the accelerator pedal and to be automatically opened by engine suction. The switch is in general of the same construction as that which is described in applicant's copending application Serial No. 653,983, but in the construction used in that application the switch could be opened by the suction just as soon as the suction was sufficient to overcome the pressure of the springs which normally hold the diaphragm of the suction unit in its normal position. In the construction shown herein, the switch of the application referred to has been modified to some extent because the present switch is designed to be opened by a lesser degree of suction than in the earlier application and means are provided in this construction to hold the switch closed after it has been closed by movement of the accelerator pedal until the latter is returned to normal position so as to prevent any possibility of suction opening the switch during the cranking of the engine by the starting motor. In the earlier switch, the suction during this period was not sufficient to effect opening of the switch, but in this form of the device the switch is held closed by so little force that the cranking suction might be sufficient to open it if means were not provided to prevent that action taking place, the switch having been constructed in this manner because the suction is the only means used to hold the switch open during the running of the engine, while in

the earlier case the generator was also adapted to perform this function. Therefore, in this construction the switch has been designed so that a very little suction is effective to keep it open, while the engine is running under its own power, otherwise when operating at wide open throttle and with heavy load, the switch might be permitted to close.

The switch is best shown in Figs. 5, 6 and 7 and comprises a cup-shaped metal housing 100 which is closed at one end by a plate of insulating material 102 secured in position by tangs 103 projecting from housing 100 and which supports the fixed contacts of the switch as is more fully described hereinafter and at the other end is closed except for a small central opening. This housing is secured by rivets 104, one of which projects into the housing 100, to form a stop for a purpose later set forth, to a sheet metal shell 106 which forms part of a diaphragm chamber, 20 a second similar shell 108 forming the other part of such chamber. These shells are flanged and their peripheries are joined in any suitable way so as to form a fluid tight joint with a flexible diaphragm 110 secured between the flanges of 25 the shells.

A supporting plate 112 has a projection 113 at its center which engages the shell 108 as indicated in Fig. 5, when the parts are assembled so as to leave a space between the outer part of the 30 plate and the shell 108. This permits machine screws 114 to be positioned in suitable holes in the plate 112 with the heads of the screws positioned between the shell 108 and the plate, said plate providing a convenient means for supporting 35 the switch unit. The screws are adapted to cooperate with some suitable bracket extending from some part of the engine or other suitable supporting means. The plate 112 is secured to the shell 108 by a nipple 116 which has a reduced 40 end 118 extending through aligned orifices in the shell and the plate, the end of this reduced portion being flanged over the inner edge of the shell to hold the shell and plate against a shoulder formed by the reduced portion of the nipple 45 as indicated in Fig. 5.

A reducing coupling 120 is screwed into the opposite end of the nipple and a suitable packing washer 122 is employed to form a fluid tight joint. The nipple is partially closed by a partition 124 50 integral therewith and an orifice 126 of relatively small size is provided therein through which the engine suction is communicated to the diaphragm. The end of the reducing coupling is threaded as indicated in Fig. 5, so as to be connected to 55 a suitable suction connection extending to the intake manifold. A cup shaped washer 128 is held against the diaphragm when the parts of the switch are assembled and received between this washer and the partition 124 in the reducing 60 coupling is a spring 130 which, when the engine is not running, is adapted to hold the parts of the switch in the position shown in Fig. 5.

Journalled in the plate of insulating material is a stud or spindle 132 to the outer end of which 65 is secured the operating arm 70 and in the outer end of the arm is an orifice 136 in which some suitable operating connection adapted to extend to the accelerator pedal may be secured. At the other end of the arm 70 is a bent-over tang 138 70 adapted to cooperate with shoulders 140 and 142 formed on a raised portion of the plate 102 which act as stops to limit the movement of the operating arm, while a lug 143 projecting from the arm is adapted to cooperate with a suitable mark on 75

the plate 102 to indicate where the arm should be positioned when adjusting its operating mechanism so that the arm will be moved to the proper extent upon operation of the accelerator pedal.

5 The arm 70 is secured by riveting or otherwise on a flattened extension 133 of the spindle or stud 132 which at the other end is provided with a reduced portion 144 which extends through an opening in a switch operating member 146 and is 10 bent over the edge of said opening to secure the switch operating member against a shoulder formed by said reduced portion 144. The member 146 has lugs 148 projecting therefrom which are adapted to operate the movable switch contact, 15 flanges 150 being provided on these lugs to engage cooperating lugs projecting from a member carried by a carrier plate which supports the movable switch contact in the manner hereinafter described. The stud or spindle 132 is provided 20 with an axial recess 151, in one end of which is supported a pin 152, on which the movable switch contact and the carrier therefor are rotatably supported and at its other end the pin 152 has a reduced extension 154 which extends through the 25 diaphragm 110 and the washer 128, being riveted over the washer so that the pin is reciprocated in an axial direction as the diaphragm moves back and forth under the influence of engine suction. Secured between an enlarged portion 156 of the 30 pin which projects through the opening in the housing 100, previously referred to, and the diaphragm 110, is a suitable metal washer 158 which serves to give the diaphragm assembly greater rigidity and strength.

35 Supported on the pin 152 immediately to the left of the enlarged portion 156 of such pin, as shown in Fig. 5, is a carrier plate of insulating material 160 which supports the movable switch contact, the carrier plate, the contact and associated parts forming a sub-assembly unit such as shown in perspective in Fig. 7. The movable contact has a ring 162 of brass or other suitable metal having three raised segments 164 thereon which form contact surfaces and are adapted to be brought into contact with the fixed contacts 40 64 and 66 carried by the plate 102 and connected to binding posts 166 and 168 respectively, to which are connected the wires 62 and 72 previously referred to. Projecting from the movable contact 45 162 in a direction normal to the contacting surface and parallel to the axis of pin 152 are lugs 170 which project through notches 172 in the carrier plate 160 and are bent over at their ends as indicated at 174 so that no relative rotary movement 50 of the contact and carrier plate can take place. A coil spring 176 which is received between the movable contact and the plate 160 normally holds the parts in such position that the bent-over portions of the lugs 170 engage the 55 carrier plate but permits movement of the movable contacts toward the carrier plate 160 under certain circumstances.

Adjacent the carrier plate 160 is a contact operating member 178 which is secured to the 60 plate by lugs 180 which project through the carrier plate and extend into notches formed in a washer 182 on the opposite side of the carrier plate while a pin 184 passes through a hole in the pin 152 to hold the carrier plate and the switch operating member 178 in position against the enlarged portion 156 of the pin 152, as shown in Fig. 5, so that the plate 160, which moves with the pin, is reciprocated by suction. As best shown in Figs. 5 and 6, the operating member 178 is provided with lugs 186 which

extend in a direction parallel to the axis of the pin 152 and normally project into spaces between the flanges 150 of the lugs 148 extending from the member 146 when not separated therefrom by engine suction, so that when the member 146 is 5 rotated the flanges 150 will engage the lugs 186 to rotate the carrier plate and the movable contact 162 supported thereby. The members 144 and 178 form a sort of switch operating clutch which is released by engine suction.

10 The carrier plate 160 is also provided with projecting lugs 188 which cooperate with the post 104 to limit the movements of the carrier plate and the switch contact carried thereby. A spring 190 is received between the washer 182 and the closed end of the housing 100 and cooperates with springs 130 and 176 to normally hold the carrier plate and the movable contact supported thereby in the position shown in Fig. 5 with the movable contact engaging the plate of insulating 20 material 102, but in such position that the contact surfaces 164 engage the surfaces of the plate 102 between the fixed contacts 64 and 66, so that in order for the contacts to be closed the arm 70 must be operated to rotate the movable 25 contact into engagement with the fixed contact. This spring 190 has one end extending through a hole in the housing 100 and the other end extends through holes formed in the washer 182 and in the plate 160 so that the spring exerts a 30 force tending to rotate the plate and the parts carried thereby in a counter-clockwise direction in Fig. 6 tending to hold the plate in the position where the lug 188 therein engages the post 104, and to return the plate 160 to this position after 35 the plate has been moved in the opposite direction to close the switch contact by operation of the arm 70. The switch construction above described is just the same as that of the earlier application referred to previously.

40 In such switch the closing of the contact is effected by operation of the arm 70 in a clockwise direction in Fig. 6. The engagement of the clutch operating member 146 with the lugs 178 rotates the carrier plate and the movable contact into a position where the segments 164 engage the contacts 64 and 66. This would effect energization of the magnet and the starting motor would immediately become operative to crank the engine which, as soon as the suction was sufficiently great, would cause the diaphragm 110 to be moved to the right carrying the carrier plate and the movable contact to the right out of engagement with the fixed contacts 64 and 66 after which movement of the spring 190 would cause rotation of the carrier plate in a direction the reverse of that in which it was moved by the arm 70, as soon as the lugs 186 were withdrawn from engagement with the operating member 146. With the carrier plate in this position if the suction dropped to such an extent that it was insufficient to overcome the spring pressure tending to move the diaphragm and associated parts to the left the contact member would be moved back into engagement with the plate of insulating material 102 to the position it originally occupied.

45 As stated previously, in this form of the switch it is not desired to have the suction operative to move the switch contact 164 to the right to disengage the contacting surfaces from the fixed contacts until the operating arm 70 has been restored to its initial position because the spring pressure holding the diaphragm, movable contact and associated parts in the left hand position is 50 so light that the suction produced during engine 55

cranking might be sufficient to open the switch. In order to prevent this action taking place, the lugs 186 in this form of switch are provided with notches 192 on that side of each of these lugs which is adapted to engage the flange 150 which projects from the switch operating member 146 when the operating arm 70 is moved to rotate said switch operating member. As the switch operating member is rotated to effect closing of the switch, the flange 150 enters the notches 192 and holds the movable contact in engagement with the fixed contacts, no matter how high the suction may be, until the operating arm is returned to its original position at which time the flange 150 is disengaged from the notches 192 and the engine suction can then move the parts to the right as previously described. After this the engine suction is effective to hold the switch contacts separated and holds the lugs 186 out of the path of movement of the flange 150 so that during operation of the engine under its own power the operating arm 70 may move with the accelerator pedal as it is operated to vary the speed of the engine without in any way affecting the switch.

In Fig. 7 is disclosed a somewhat modified form of switch which is of exactly the same construction as that previously described except for the fact that the notches 192 are omitted and the plate of insulating material 102a which is of the same construction and arrangement as the plate 102 previously described, is adapted to be moved relative to the housing corresponding to the housing 100 in order to enable the switch to be normally closed, if so desired. For this purpose the plate of insulating material as shown in Fig. 7, is provided with two notches 200 and 202 and it may be so adjusted that the retaining tangs or lugs corresponding to the lugs 103 of the switch previously described may engage either the notches 200 or the notches 202. If so adjusted that the lugs engage the notch 200 the switch will operate as previously described and it will be necessary to move the operating arm 70 in order to effect closing of the switch. If the plate of insulating material carrying the fixed contacts is, however, adjusted so that the lugs engage the notches 202, the fixed contacts will be in such position that they will be engaged by the movable contact when the parts are in the normal position they occupy when the engine is not operating. If the insulating plate is so adjusted, the closing of the ignition switch will complete the circuit through the winding of the magnet 55 and no operation of the switch A will be necessary, to cause the starting motor to become operative. Thus the semi-automatic control device previously described and shown in copending application 653,983, may by means of a simple adjustment of the switch A, be changed to a full-automatic device. In such construction the suction is operative to separate the movable contact from the fixed contacts in the manner previously described. When the engine is started the accelerator pedal would of course, move the operating arm 70 from its original position when the pedal is moved to accelerate the engine, so that the flange 150 would be moved to a position where the lugs 186 would engage such flange in the event that the engine suction fell to such a degree that it would be insufficient to overcome the effect of the various springs which normally move the diaphragm and associated parts toward the left, in order that the switch could not be closed

during operation of the engine even if the suction were insufficient to hold it open.

In the diagram disclosed in Fig. 2 the control system is exactly the same as that previously described in construction and operation with one exception. Instead of employing a starting motor and a starter drive of the Bendix type, in Fig. 2 the electromagnet operates not only to close the starting switch, but to shift the driving pinion of an over-running clutch type of starter into engagement with the engine flywheel gear. The parts of the construction which are the same as that previously described are indicated in Fig. 2 by the same reference numerals with the suffix "b" added. It will be noted that the armature of the magnet 24b is connected by a pin and slot connection 210 to a lever 212 pivoted at 214 and having a yoke at its lower end, from the arms of which pins 216 project and engage a collar 218 slidable on a sleeve 220 which is splined on the armature shaft 224 of the starting motor 20b. The sleeve is formed integrally with one of the cooperating members of an over-running clutch indicated in its entirety as 226, the other member of which is integral with or secured to the driving pinion 228 which is adapted to engage the flywheel gear 230. This starter drive is the conventional overrunning clutch type and its construction and operation need not be more specifically described. It is obvious that when the magnet is energized the lever 212 is rocked to move the driving pinion 228 into engagement with the gear 230 by compression of a spring 232 which surrounds the sleeve 220 between the collar 218 and the clutch. As the pinion is meshed with the gear 230, the starting motor switch is closed and the starting motor becomes operative to crank the engine. The starting motor circuit is broken by engine suction as previously described and upon deenergization of the magnet 24b, a spring 234 is operative to return the lever 212 and the parts moved thereby to their original position disengaging the driving pinion 228 from the flywheel gear.

In Fig. 3 the arrangement of the magnet, the starting motor and the starter drive is exactly the same as shown in Fig. 2, but instead of employing a switch operable by the accelerator pedal and opened by engine suction to control the magnet, the latter is controlled by a manually operable push button. Parts in this figure which are of the same construction as those previously described are given the same reference numerals with the suffix "c" added thereto. It will be apparent on inspection of Fig. 3 that a wire corresponding to the wire 62 and numbered 240 leads from the wire 60c which extends from the ignition switch to the ignition system and connects with a fixed contact 242 of a manually controlled switch having a push button 244 carrying the movable contact 246 which is adapted to engage another fixed contact 248 connected by a wire 250 with the coils 59c, and 52c of the magnet, these coils being respectively grounded by the wire 14c and connected to the wire 28c leading to the starting motor by a wire 76c. The function of this device is exactly the same as that previously described except for the fact that the control of the magnet is entirely manual. The magnet is energized when the ignition switch is closed and the push button 244 is operated to close the manually operable switch and remains energized as long as the push button is held in position to close said switch. Upon release of the push button, the magnet is de-energized and

the starting motor rendered inoperative so that the parts return to their normal position as previously described.

While the embodiment of the present invention 5 as herein disclosed, constitutes a preferred form, it is to be understood that other forms might be adopted, all coming within the scope of the claims which follow.

What is claimed is as follows:

10 1. Control apparatus for internal combustion engines comprising, in combination, a starting motor, a current source adapted to supply current to said starting motor, a switch comprising fixed and movable contacts for effecting connection between the current source and said starting motor, means for operating said movable contact to close said switch, means operable by the engine for opening said switch, and means for preventing opening of said switch by the engine 15 until the means for operating said movable contact is returned to normal position.

20 2. Control apparatus for internal combustion engines comprising, in combination, a starting motor, a current source adapted to supply current to said starting motor, a switch comprising fixed and movable contacts for effecting connection between the current source and said starting motor, means for operating said movable contact to close said switch, means operable by the engine for opening said switch and adapted 25 to open the switch when the engine is operating at very low speed and means for preventing the opening of the switch until the means for operating said movable contact is returned to normal position, whereby opening of the switch during cranking of the engine is prevented.

30 3. Control apparatus for internal combustion engines comprising, in combination, a starting motor, a current source adapted to supply current to said starting motor, a switch comprising fixed and movable contacts for effecting connection between the current source and said starting motor, means for operating said movable contact to close said switch, means operable by engine suction for holding said switch open during 35 operation of said engine and means for holding the switch closed against the action of the suction until the means for operating said movable contact is returned to normal position.

40 4. Control apparatus for internal combustion engines comprising, in combination, a starting motor, a current source adapted to supply current to said starting motor, a switch comprising fixed and movable contacts for effecting connection between the current source and said starting motor, means for operating said movable contact to close said switch, means operable by engine suction for holding said switch open during operation of the engine and adapted to become effective to open the switch at very low 45 engine speed, and means for holding the switch closed against the action of the suction until the means for operating said movable contact is returned to normal position.

50 5. Control apparatus for internal combustion engines comprising, in combination, a starting motor, a current source adapted to supply current to said starting motor, a switch comprising fixed and movable contacts for effecting connection between the current source and said starting motor, means for operating said movable contact to close said switch and adapted to be held in its switch closing position during the cranking of the engine, means operated by engine suction 55 for automatically opening the switch and so con-

structed that the suction is sufficient during cranking of the engine to operate said switch opening means, and means for holding the switch closed against the action of the suction until the means for operating said movable contact is returned to normal position, whereby opening of the switch during engine cranking is prevented.

6. Control apparatus for internal combustion engines comprising a current source, a starting motor operated by current from said source, a switch for controlling the connection of the starting motor with the current source, said switch comprising a fixed contact, a movable contact rotatably mounted, means for moving said contact into position to engage the fixed contact, means operable automatically by the engine for moving the movable contact along its axis of rotation to separate the switch contacts and means for preventing axial movement of said movable contact until the means for rotating said contact has been returned to its normal position.

7. Control apparatus for internal combustion engines comprising a current source, a starting motor operated by current from said source, a switch for controlling the connection of the starting motor with the current source, said switch comprising a fixed contact, a movable contact rotatably mounted, means for moving said contact into position to engage the fixed contact, means operable automatically by the engine for moving the movable contact along its axis of rotation to separate the switch contacts, means for preventing axial movement of said movable contact until the means for rotating said contact has been returned to its normal position and means for preventing closing of the contacts after the switch has been opened by the engine as long as the engine continues to run.

8. Control apparatus for internal combustion engines comprising a current source, a starting motor operated by current from said source, a switch for controlling the connection of the starting motor with the current source, said switch comprising a fixed contact, a movable contact rotatably mounted, means for moving said contact into position to engage the fixed contact, means operable by engine suction for moving the movable contact along its axis of rotation to separate the switch contacts, and means for preventing movement of said movable contact by engine suction until the means for rotating said contact has been returned to its normal position.

9. Control apparatus for internal combustion engines comprising a current source, a starting motor operated by current from said source, a switch for controlling the connection of the starting motor with the current source, said switch comprising a fixed contact, a movable contact rotatably mounted, means for moving said contact into position to engage the fixed contact, means operable by engine suction for moving the movable contact along its axis of rotation to separate the switch contacts, means for preventing movement of said movable contact by engine suction until the means for rotating said contact has been returned to its normal position, and means for preventing closing of the contacts after the switch has been opened by engine suction as long as the engine continues to run.

10. Control apparatus for internal combustion engines comprising a current source, a starting motor operated by current from said source, a switch for controlling the connection of the starting motor with the current source, said switch comprising a fixed contact, a movable contact

5 rotatably mounted, means for moving said contact into position to engage the fixed contact and adapted to be held in switch closing position during the cranking of the engine by the starting 5 motor, means operable by engine suction for moving the movable contact along its axis of rotation, the engine suction being sufficient to move said contact during cranking of the engine, and means for preventing movement of the movable 10 contact by suction until the means for rotating said contact has been returned to its normal position.

11. Control apparatus for internal combustion engines comprising a current source, a starting 15 motor operated by current from said source, means for controlling the quantity of combustible mixture supplied to the engine, a switch for controlling the connection of the motor with the current source, said switch comprising a fixed 20 contact, a movable contact rotatably mounted, means operated by said mixture controlling means into position to engage the fixed contact, means operable automatically by the engine for moving the movable contact along its axis of 25 rotation to separate the switch contacts and means for preventing axial movement of said movable contact until the means for rotating said contact has been returned to its normal position.

30 12. Control apparatus for internal combustion engines comprising a current source, a starting motor operated by current from said source,

means for controlling the quantity of combustible mixture supplied to the engine, a switch for controlling the connection of the motor with the current source, said switch comprising a fixed contact, a movable contact rotatably mounted, 5 means operated by said mixture controlling means into position to engage the fixed contact, means operable by engine suction for moving the movable contact along its axis of rotation to separate the switch contacts, and means for preventing movement of said movable contact by engine suction until the means for rotating said contact has been returned to its normal position. 10
13. Control apparatus for internal combustion engines comprising a current source, a starting 15 motor operated by current from said source, a switch for controlling the connection of said starting motor with the current source and comprising a rotatable carrier plate, a movable contact mounted thereon, means for rotating the 20 carrier plate to bring the contacts into engagement, means operable by the engine for moving the carrier plate and the contact carried thereby bodily in a direction substantially normal to the surface of the fixed contact to open the switch 25 when the engine is running, and means for preventing the movement of said carrier plate and movable contact by the engine until the operating means for the carrier plate has been returned to normal position.
